US00D519477S

(12) **United States Design Patent** (10) **Patent No.:** **US D519,477 S**
Liu et al. (45) **Date of Patent:** **** Apr. 25, 2006**

(54) **PORTABLE RADIO HOUSING**

(75) Inventors: **Lan-Ting Liu**, Sunrise, FL (US);
Jeffrey Wayne Ashton, Sunrise, FL (US); **Yesenia V. Escoria**, Plantation, FL (US); **Craig F Siddoway**, Davie, FL (US)

(73) Assignee: **Motorola, Inc.**, Schaumburg, IL (US)

(**) Term: **14 Years**

(21) Appl. No.: **29/215,164**

(22) Filed: **Oct. 14, 2004**

(51) **LOC (8) Cl.** **14-03**

(52) **U.S. Cl.** **D14/137**

(58) **Field of Classification Search** D14/137, D14/191, 383–385, 496, 188, 358, 240, 192, D14/194, 197, 198, 225, 159, 155, 417; 340/539.11, 340/573.3, 573.4, 573.1; 361/814; 455/90.3, 455/575.1, 90.2, 347–349, 351; D10/104, D10/106

(57) **CLAIM**

The ornamental design for a portable radio housing, as shown and described.

DESCRIPTION

FIG. 1 is an isometric view of a portable radio housing showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown in FIGS. 1–7 are included for the purpose of illustrating environmental elements only and form no part of the claimed design.
